UNITED STATES PATENT OFFICE

PERCIVAL K. REED, OF LLANERCH, PENNSYLVANIA, ASSIGNOR TO ATLAS CONVEYOR COMPANY, OF PHILADELPHIA, PENNSYLVANIA, A CORPORATION OF PENNSYLVANIA

SKIP HOIST

Application filed September 27, 1929. Serial No. 395,493.

My invention relates to skip hoists, and it relates more particularly to improved means for feeding material from the hopper to the bucket when the bucket is in the loading position at the bottom of the hoist.

5 The principal object of my present invention is to provide an improved form of apparatus for loading the bucket from the hopper of a skip hoist structure, which is so constructed and arranged that the flow of the material from the hopper will be automatically stopped when a predetermined weight of the material has been delivered to the bucket.

10 A further object of my invention is to provide apparatus of the character aforesaid, which is so constructed and arranged that possibility of spilling of the material at the bottom of the hoist will be reduced to a minimum.

15 A further object of my invention is to provide apparatus of the character aforesaid, which is so constructed and arranged that the control switch for the operation of the bucket may be readily actuated when a predetermined weight of the material has been delivered to the bucket.

20 A further object of my invention is to provide apparatus of the character aforesaid, which is so constructed and arranged that positive closing of the gate will be insured whenever the bucket starts on its upward travel from its loading position at the bottom of the hoist.

25 A further object of my invention is to provide apparatus of the character aforesaid, which is so constructed and arranged that possibility of "smashes", due to improper operation of the bucket, will be eliminated.

30 With the foregoing objects in view, my invention contemplates the provision, in a skip hoist, of novel mechanism for opening and closing the gate which controls the delivery of the material from the hopper to the bucket.

35 The nature and characteristic features of my invention will be more readily understood from the following description, taken in connection with the accompanying drawings

40 Figure 1 is a side elevation of the lower portion of a skip hoist, showing mechanism embodying the main features of my present invention, the bucket being shown in the loading position, and certain of the structural supporting members being shown in section and others being omitted for clearness of illustration. 45

45 Fig. 2 is a vertical, central, sectional view of the structure shown in Fig. 1; 50

50 Fig. 3 is a rear elevation of the lower or gate portion of the hopper and the parts associated therewith;

55 Fig. 4 is a plan view of that portion of the mechanism which is adapted to control the 55 closing of the gate when a predetermined amount of the material has been delivered to the bucket;

60 Fig. 5 is a side elevation of the portion of the apparatus shown in Fig. 1, the gate structure being shown in the closed position, and the bucket being shown in an intermediate position; 70

65 Fig. 6 is an enlarged detail view of the latch mechanism; 75

70 Fig. 7 is an underneath plan view thereof;

75 Fig. 8 is an enlarged sectional detail view showing a device for limiting the movement of the gate structure at the closed position, the section being taken on the line 8—8 of 80 Fig. 5; and

80 Fig. 9 is a view of a modified form of the latch mechanism.

85 It will, of course, be understood that the drawings and description herein contained are illustrative merely, and that various modifications and changes may be made in the structure without departing from the spirit of my invention.

90 Referring to the drawings, in the particular embodiment of my invention therein shown, 10 is the skip hoist bucket, which may be of any preferred shape. The bucket 10 is guided in its movement by wheels 11, mounted upon an axle 12, which is secured to the rear wall of the bucket near the top thereof. Another pair of wheels 14 is mounted upon an axle 15, secured to the under side of the bucket. 95

95 A bail structure 16 is pivotally connected, 100

as at 17, to the side walls of the bucket. An axle 18 is mounted in the top cross strut 19 of the bail structure, and upon the ends of this axle wheels 20 are mounted.

The wheels 11, 14 and 20 are guided between tracks 21, provided at the sides of the skip hoist structure. The tracks 21 extend upwardly in any desired direction, according to the requirements of the particular hoist, the lower portions thereof serving to guide the bucket to the proper loading position.

A hoisting cable 22 is connected in any suitable manner to the cross strut 19 of the bail structure 16, whereby the bucket may be raised and lowered in the operation of the hoist.

The hopper 23 is provided at its bottom with an inclined chute 24, which extends toward the bucket when the same is in the loading position. Within the chute 24 there is located a depending baffle plate 25, preferably weighted, as at 26, and hinged as at 27, to a portion of the chute 24.

The baffle 25, being weighted and pivoted as above described, serves to retard or thin out the flow of the material through the chute 24, while at the same time permitting the larger lumps to pass, thus preventing choking of the outlet. The baffle 25 also serves to prevent ricocheting of pieces of the material out of the chute when the material is being fed rapidly and in a thin stream through the hopper without having previously accumulated therein.

Upon the under side of the chute 24 there is mounted a transverse shaft 29, and by means of this shaft the side frames 30 of the gate structure are journaled. The gate proper comprises a sector plate 31, secured at its edges to the frames 30.

The frames 30 also carry an auxiliary chute 32, which in the loading position extends forwardly from the lower edge of the bottom plate of the chute, to carry the material passing from the chute into the bucket.

The front plate of the bucket 10 is cut out as at 33, to permit the auxiliary chute 32 to extend into the same. Immediately below the cut out portion the bucket is provided with a reinforcing plate 34, which extends across the inside of the bucket.

Each of the side frames 30 of the gate structure is provided with a rearwardly extending arm 35. The arms 35 are connected at their free ends by means of a transverse bar 36. The ends of the bar 36 extend beyond the arms 35, whereby counterweights 37 of suitable mass may be mounted thereon. The mass of the counterweights 37 is such that the gate structure normally tends to move to the closed position about the axis provided by the shaft 29.

Mounted upon the under surface of the bottom plate 38 of the chute 24 is a bracket

39, in which a rod 40 is slidably mounted. The upper end of the rod 40 is enlarged as at 41, and in this enlarged portion there is journaled a roller 42. The roller 42 is adapted to engage the bar 36 which is carried at the ends of the arms 35 of the gate structure, serving to retain the gate structure normally in the open position while the bucket is being loaded.

The roller 42 is impelled to its operative position by means of a coil spring 43, which is mounted upon the rod 40. The coil spring 43 bears at one end against a portion of the bracket 39, and at its other end against the enlarged portion 41 of the rod 40. Upon the lower end of the rod 40 there are mounted lock nuts 44.

It should here be noted that the tension of the coil spring 43 is such that the roller 42 will normally, by its engagement with the transverse bar 36, retain the gate structure in the open position, but on the other hand, said roller may be depressed whenever the gate structure is impelled to or from the open position, to allow the bar 36 to pass behind the same and be there retained.

The bracket 39 also serves as a means for supporting a pin 45, upon which a bell crank lever 46 is pivotally mounted. Interposed between the lock nuts 44 and the lower end of the bracket 39 is a trunnioned collar 47, which is slidably mounted on the rod 40, and is engaged by one end of the bell crank lever 46. The other arm of the bell crank lever 46 is pivotally connected, as at 48, to one end of a connecting rod 49. The other end of the connecting rod 49 is pivotally connected, as at 50, to a bracket member 51, which is carried by a cross bar 52 of the weight determining device.

The cross bar 52 is carried at the rear ends of a pair of levers 53. The levers 53 are journaled by means of a transversely extending shaft 54. The shaft 54 is supported by means of brackets 55, which are in turn supported by means of rigid transverse beams 56. The front ends of the levers 53 support a transversely extending shaft 57, upon which a pair of rollers 58 is mounted.

The bucket 10 is provided on its front wall with a pair of shoes 59, which are so positioned as to engage and bear against the rollers 58 when the bucket is in the loading position.

The bracket member 51, to which the connecting rod 49 is attached, also has pivotally connected therewith, as at 60, one end of a connecting rod 61. The other end of the connecting rod 61 is pivotally connected, as at 62, to a lever arm 63. One end of the lever arm 63 is pivotally mounted, as at 64, in a fixed bracket member 65.

Upon the free end of the lever 63 counterweights 66 are adjustably mounted. The free end of the lever 63 normally rests upon

a bumping block 67, which serves to limit the downward movement of the free end of said lever, said block being supported by means of brackets 68 secured to the beams 56.

Upon the shaft 29, by means of which the gate structure is pivoted, there is also pivotally mounted a pair of arms 70, which extend along the sides of the frames 30 of the gate structure, and which are connected at their free ends by means of a transversely extending shaft 71.

Upon the shaft 71 there is mounted a pair of rollers 72, which are adapted to be engaged by the shoes 59 which are carried by the bucket 10. Upon the side frames 30 of the gate structure there are provided projecting lugs 73, upon which the arms 70 normally rest.

On each side of the chute 24 there is provided a device for arresting and limiting the movement of the gate structure when the same reaches the closed position. Each of these devices comprises a spring plate 75, one end of which is bolted, as at 76, to the side plates of the chute 24, and the other end of which extends outwardly therefrom, whereby the same will be frictionally engaged by the side frames 30 of the gate structure when the same is in the closed position.

The extreme end of the plate member 75 is bent outwardly at right angles, as at 77, to form a stop against which the frame 30 will impinge when the gate reaches the closed position. The portion 77 of the plate 75 which extends outwardly at right angles has secured thereto one arm of an angle bracket 78. The other arm of the angle bracket 78 engages a bolt 79, upon which a coil spring 80 is mounted, the coil spring being interposed between the angle bracket 78 and the side plate of the chute 24. The coil spring 80 tends to hold the spring plate 75 in its normal position to engage frictionally the side frames 30 of the gate structure. By the foregoing arrangement, the gate structure will be held in the closed position, and accidental opening of the gate when the bucket is away from the loading position will be prevented.

Nuts 81 are provided on the bolt 79, serving to permit adjustment of the outward extension of the plate 75, whereby the frictional engagement thereof with the side frames 30 of the gate structure may be adjusted.

By properly adjusting the nuts 81 on the bolt 79, the arrangement will be such that as the gate structure approaches its closed position, the side frames 30 thereof will first frictionally engage the spring plates 75, whereby the momentum of the gate structure will be decreased and the shock minimized when the side frames finally impinge against the portions 77 of the plate member 75, which are bent outwardly at right angles to form a stop.

A control switch 90 may be fixedly mounted in connection with the weight determining

device, this switch having a depending operating lever 91, the lower end of which carries a roller 92. The roller 92 is adapted to be engaged by a finger 93 which may be secured to the connecting rod 61, or any other suitable moving part of the weight determining device, whereby the control switch 90 may be automatically manipulated whenever the parts with which the connecting rod 61 is connected are caused to be actuated in the manner to be hereinafter more fully explained.

For the proper relative adjustment of the several parts, the connecting rod 49 may be provided with an adjusting turnbuckle 95, and likewise the connecting rod 61 may have interposed therein an adjusting turnbuckle 96.

The operation of the device may now be explained. The bucket 10 being in the position shown in Figs. 1 and 2 of the drawings, and the gate being in the open position also therein shown, the material will flow from the hopper 23 through the chute 24. The material thus passing through the chute 24 will be retarded by the weighted and pivoted baffle 25, so that the normal stream of the material will be defined by the lower edge of the baffle 25, while at the same time any large lumps which may be in the material will be permitted to pass; and also, by means of the baffle 25, pieces of the material will be prevented from ricocheting out of the chute into the pit of the hoist, as frequently occurs when the hopper is empty and the stream of material is relatively thin and is passing rapidly through the hopper and chute.

It has been found in practice that, by the provision of the baffle arranged as herein described, substantial uniformity of the load in the bucket is obtained, notwithstanding variations in the amount of material which may accumulate in the hopper during the periods when the bucket is away from the loading position.

When a predetermined weight of the material has passed into the bucket, the shoes 59 which bear against the rollers 58 will cause the other ends of the levers 53 to be raised. This motion will be transmitted by means of the cross bar 52, through the connecting rod 49 to the bell crank lever 46.

When the bell crank lever 46 is thus actuated, the rod 40 will be depressed against the tension of the spring 43, whereupon the roller 42 will be retracted from its engagement with the bar 36. The gate structure will now be free, whereupon the counterweights 37 will cause the gate to be moved about the axis provided by the shaft 29, and the gate will be swung to the closed position shown in Fig. 5 of the drawings.

As the auxiliary chute 32 forms a component part of the gate structure, the same will be moved out of the path of travel of the

bucket when the gate is moved to the closed position.

As hereinbefore pointed out, the gate structure is limited in its movement to the closed position by means of the spring plates 75, the faces of which will frictionally engage the side frames 30 of the gate structure, and the projecting portions 77 thereof will form abutments against which the upper edges of the side frames 30 will impinge when the gate is in the closed position.

It will be noted that when the gate is swung to the closed position, the rollers 72, which are mounted upon the shaft 71, which in turn is carried by the arms 70, will be brought to such position as to be in the path of the shoes 59 which are carried by the bucket.

However, as the arms 70 merely rest upon the projecting lugs 73, which extends from the side frames 30 of the gate structure, said rollers may be swung sufficiently about the axis provided by the shaft 29 so as not to interfere with the upward travel of the bucket, and it will be seen that after the shoes 59 have passed to a point to clear the rollers, the arms 70 will then return by gravity to rest again upon the lugs 73, so that the rollers will be in the proper position to be encountered by the shoes upon the return movement of the bucket.

After the bucket has discharged its load, in the customary manner, at the top of the hoist, and returns for another load, the shoes 59, in the downward movement of said bucket, will encounter the rollers 72, whereupon, by reason of the arms 70 bearing against the lugs 73 of the side frames 30 of the gate structure, the gate structure will be pushed by the bucket to the open position, as shown in Figs. 1 and 2 of the drawings. The action above described takes place, of course, upon each movement of the bucket to and from the loading position.

It will be seen that the mechanism above described for causing the gate to be closed will be brought into action when a predetermined weight of the material has been delivered to the bucket, the amount of said weight being determined by the mass and position of the weights 66, which are adjustably mounted upon the free end of the lever 63, which, as hereinbefore described, is connected by means of the connecting rod 61 to the structure associated with the levers 53.

It will also be seen that when the levers 53 are actuated as above described, the finger 93, which is carried by the connecting rod 61, will engage the roller 92 carried at the end of the operating arm 91 on the control switch 90. In this manner, the switch 90 may be actuated, so that, by mechanism with which the present application is not particularly concerned, the bucket may be automatically

started upon its upward travel after the same has received its proper load.

It may here be noted that, should the means for releasing the gate to permit the same to swing to its closed position fail to operate from any cause prior to the starting of the bucket upon its upward travel, no particular harm will be done, as the horizontal edge of the cut out portion 33 of the bucket 10 will engage the auxiliary chute 32 of the gate structure, whereupon the gate will be pulled by the bucket to the closed position. When the action takes place in this manner, the bar 36 will be forced over the roller 42, causing the rod 40 to be retracted sufficiently against the tension of the spring 43, to permit the bar 36 to pass and the gate structure thus freed.

In fact, in some instances, the connecting rod 49 and the bell crank lever 46 may be omitted entirely, and the closing of the gate effected by the engagement of the bucket with the auxiliary chute 32. When the gate is closed by means of the bucket, as above described, it will be understood that after the bar 36 has been released from engagement with the roller 42, the counterweights 37 will function in the usual manner to bring the gate structure to the fully closed position, so that the parts will be in the proper position to be again actuated upon the return of the bucket.

It will be seen that there is thus provided a novel, simple, and efficient mechanism for loading the bucket from the hopper of a skip hoist structure, which is so constructed and arranged that the flow of material from the hopper will be automatically stopped when a predetermined weight of the material has been delivered to the bucket, in which likelihood of spilling of the material at the bottom of the hoist will be minimized, in which the control switch for the actuation of the bucket may be actuated when the bucket is loaded, in which positive closing of the gate will be insured whenever the bucket starts on its upward travel from its loading position, and in which possibility of damage through improper operation of the bucket will be eliminated.

I claim:

1. In a skip hoist, means for loading the bucket comprising a chute; a gate structure movably mounted with respect to said chute and having a portion adapted to extend across the end thereof; counterweights adapted to impel the gate structure to the closed position; means for impelling the gate structure to the open position comprising shoes carried by the bucket, and a device adapted to be engaged by said shoes as the bucket descends to the loading position, said device engaging a portion of the gate structure and normally moving in unison therewith but adapted to be pushed by the shoes.

out of the path of travel thereof when the bucket ascends after the gate has moved toward or to the closed position; and a latch member adapted normally to retain the gate structure in the open position, said latch member being independent of the means for impelling the gate structure to the open position.

2. In a skip hoist, means for loading the bucket comprising a chute; a gate structure movably mounted with respect to said chute and having a portion adapted to extend across the end thereof; counterweights adapted to impel the gate structure to the closed position; means for impelling the gate structure to the open position comprising shoes carried by the bucket, and a device adapted to be engaged by said shoes as the bucket descends to the loading position, said device engaging a portion of the gate structure and normally moving in unison therewith but adapted to be pushed by the shoes out of the path of travel thereof when the bucket ascends after the gate has moved toward or to the closed position; a latch member independent of the means for impelling the gate structure to the open position, said latch member engaging a portion of the gate structure when the gate is in the open position, said latch member being adapted to retain the gate in the open position but being retractable by a portion of the gate structure when the gate structure is impelled in either direction; and means for retracting said latch member when a predetermined weight of material has been delivered to the bucket.

carried by the bucket, and a device adapted to be engaged by said shoes as the bucket descends to the loading position, said device engaging a portion of the gate structure and normally moving in unison therewith but adapted to be pushed by the shoes out of the path of travel thereof when the bucket ascends after the gate has moved toward or to the closed position; a latch member independent of the means for impelling the gate structure to the open position, said latch member engaging a portion of the gate structure when the gate is in the open position, said latch member being adapted to retain the gate in the open position but being retractable by a portion of the gate structure when the gate structure is impelled in either direction; and means for retracting said latch member when a predetermined weight of material has been delivered to the bucket.

In testimony whereof, I have hereunto signed my name.

PERCIVAL K. REED.
